(57) **CLAIM**

The ornamental design for a front fender of motorcycles, as shown and described.

DESCRIPTION

FIG. 1 is a front view of a front fender of motorcycles showing my new design;

FIG. 2 is a rear view thereof;

FIG. 3 is a plan view thereof;

FIG. 4 is a bottom view thereof;

FIG. 5 is a right side view thereof;

FIG. 6 is a left side view thereof;

FIG. 7 is a perspective view thereof as seen from the right front side;

FIG. 8 is a perspective view thereof as seen from the left front side;

FIG. 9 is a perspective view thereof as seen from the right rear side; and,

FIG. 10 is a perspective view thereof as seen from the left rear side.

The broken lines shown are for illustrative purposes only and form no part of the claimed design.
